UNITED STATES PATENT OFFICE

152,641

DESIGN FOR A CONDIMENT SHAKER

Henry E. Musselman and William H. Buck,
Kalamazoo, Mich.

Application June 5, 1947, Serial No. 139,468

Term of patent 7 years

(Cl. D44—22)

To all whom it may concern:

Be it known that we, Henry E. Musselman and William H. Buck, citizens of the United States, residing at Kalamazoo, in the county of Kalamazoo, State of Michigan, have invented a new, original, and ornamental Design for Condiment Shakers, of which the following is a specification, reference being had to the accompanying drawing, forming part thereof.

Fig. 1 is side elevation; and

Fig. 2 is a plan view of a condiment shaker, showing our new design.

We claim:

The ornamental design for a condiment shaker, as shown.

HENRY E. MUSSELMAN.
WILLIAM H. BUCK.
